UNITED STATES PATENT OFFICE.

CHARLES W. BULLARD, OF CHICAGO, ILLINOIS.

DOOR-HANGER.

SPECIFICATION forming part of Letters Patent No. 254,605, dated March 7, 1882.

Application filed January 26, 1882. (No model.)

To all whom it may concern:

Be it known that I, CHARLES W. BULLARD, a citizen of the United States, residing at the city of Chicago, in the county of Cook and State of Illinois, have invented certain new and useful Improvements in Door-Hangers, which are fully set forth in the following specification, reference being had to the accompanying drawings, in which—

10 Figure 1 is an end elevation of a door-hanger provided with my improvements. Fig. 2 is a section on the line *x x* in Fig. 1. Fig. 3 is a transverse vertical section of the sheave in detail, the joint-bolt being shown in dotted lines.

15 Fig. 4 is a section on the line *y y* in Fig. 3. The same letters denote the same parts in all the figures.

My invention relates to apparatus for the suspension of sliding doors, and particularly 20 to such apparatus in which the door is held up by joint-bolts having their bearing directly or indirectly on sheaves which run on a double track above the door. In Patent No. 233,836, issued November 2, 1880, I have shown such a 25 device, in which the bolts are secured at their upper ends to a bearing-rail resting on the axles of a pair of sheaves, and I still regard this as the best apparatus where thoroughly 30 substantial work is requisite. In order, however, to avoid an expense unnecessary for the lighter classes of work, and secure at the same time the advantages of propelling the door with a minimum of friction and of maintaining its balance, even when the studding has sagged, 35 I have devised the apparatus which I will now proceed to describe.

In the drawings, A denotes the studding of the double partition within which the door-hanger is set. B denotes the track-rails bolted 40 to the studding, C the wheels, and C' the cylindrical axle of the sheave which runs on this track, the wheels being rigidly affixed to the axle. None of these present any feature of novelty.

On the axle I set a box or washer, D, as close as is consistent with allowing the axle to turn freely within it. This box, which is preferably made of anti-friction metal, is rectangular in fundamental form, the axle passing through it a little above the middle point of 50 its altitude. On the top and at the ends it has a cylindrical groove, d, adapted to receive the hooked upper end of a cylindrical joint-bolt, E, the lower end of which is affixed to the door F near one of its upper corners, the 55 other upper corner having of course a similar bolt resting in the same way on a similar box and sheave. By this arrangement the entire friction incident to the propulsion of the door is confined to the contiguous surfaces of the 60 box D and the axle C', the joint-bolt and the box having no motion relatively to each other. The friction and consequently the wear are thus much less than if a joint-bolt of iron or other practicable material were directly in contact with an iron axle. 65

On account of the cylindrical form of the joint-bolt, the bolt, and consequently the door, remain perpendicular, although by reason of sagging, one of the track-rails B may be higher 70 than the other. The conformation of the groove d obviously admits of the box turning on the cylindrical portion of joint-bolt E in such a case.

What I claim as my invention, and desire to 75 secure by Letters Patent, is—

1. The joint-bolt E, cylindrical and hooked at its upper end, in combination with the sheave C C', substantially as and for the purpose described. 80

2. The joint-bolt E, in combination with the box D and sheave C C', substantially as and for the purpose described.

CHARLES W. BULLARD.
